CLAIM

The ornamental design for a luggage carrier for bicycles or the like, as shown and described.

DESCRIPTION

FIG. 1 is a perspective view of a luggage carrier for bicycles or the like showing my new design;

FIG. 2 is a top plan view thereof;

FIG. 3 is a side elevational view thereof looking from the right of FIG. 1;

FIG. 4 is a side elevational view thereof showing the side opposite to that shown in FIG. 3;

FIG. 5 is a rear elevational view thereof; and

FIG. 6 is a front elevational view thereof.

The characteristic feature of my design resides in the specific appearance of the skirt attached to the rear of the luggage carrier.
